United States Patent Office.

F. BUXTON AND GEORGE CROSBY, OF LAKE VILLAGE, NEW HAMPSHIRE.

Letters Patent No. 79,203, dated June 23, 1868.

IMPROVED EDGE-PLANE FOR BOOTS, &c.

The Schedule referred to in these Letters Patent and making part of the same.

TO ALL WHOM IT MAY CONCERN:

Be it known that we, F. BUXTON and GEORGE CROSBY, of Lake Village, in the county of Belknap, and State of New Hampshire, have invented a new and useful Improvement in Edge-Planes for Boots and Shoes; and we do hereby declare that the following is a full and exact description thereof, reference being had to the accompanying drawings, and to the letters of reference marked thereon.

The nature of our invention consists in constructing edge-planes for planing the edges of soles of boots and shoes, with an adjustable guard-plate; also with a bolster, against which a portion of the hand rests, to allow the hand to be as near the cutter as possible, which renders the labor much easier, at the same time protects the hand from injury; also, of a peculiarly-shaped throat, to insure the free and easy discharge of the chips.

To enable others skilled in the art to make and use our invention, we will proceed to describe its construction and operation.

Figure 1 is a side view.

Figure 2 is a front edge view.

Figure 3 is a top view of the gauge H.

A is the handle.

B the body or stock, to which the several parts are connected.

C is a knife or cutter, which extends from C to the face of the plane, fitting the slot in which it rests; its cutting-edge projecting the necessary distance beyond the face of the plane to cut properly, as shown by dotted lines, fig. 1.

E is an adjustable guard, with its edge F projecting beyond the face of the plane. This guard is to protect the "upper" of a boot or shoe from injury by contact with the cutter on some kinds of work; it also bears on the outer edge of cutter C, and by means of the screw D holds it in place. The hole in the guard-plate, through which screw D passes, is a slot, as also is the hole through which the steady-pin I passes. These slots allow the edge F of the guard-plate to be projected any required distance beyond the face of the plane, or set back from the face, as is sometimes required.

G is a curved throat, so constructed to insure the perfect discharge of the chips.

H is an adjustable gauge, to govern the width of cut, or adapt it to thick or thin soles, by increasing or diminishing the distance between the guard-plate and gauge.

Fig. 3 is a top view of the gauge. The screw J passes through the slot into the projection K. This projection is a little wider than the slotted part of the gauge, and has a lip, L', extending a short distance up the outsides of the gauge, to guide it while adjusting it, and properly keep it in place, shown in fig. 2.

The part L is curved and rounded as a bolster, for the edge of the hand to press against, its form being such as to be easy to the hand, and not liable to injure it, (the hand,) it being necessary to get the hand as near the cutter as possible, which renders it easier to operate, by lessening the leverage and consequent strain on the wrist.

This plane is used the same as planes in general use, except it should be held so the edge of the hand shall rest on the bolster or part L.

What we claim as our invention, and desire to secure by Letters Patent, is—

The adjustable guard-plate E, constructed substantially in the manner and for the purpose described and set forth.

We also claim constructing edge-planes with a bolster or part, L, substantially as described and for the purpose set forth.

F. BUXTON,
GEORGE CROSBY.
